UNITED STATES PATENT OFFICE.

RICHARD J. SCHWEITZER, OF CHICAGO, ILLINOIS.

SEALED JOINT.

1,005,751.

Specification of Letters Patent. Patented Oct. 10, 1911.

Application filed June 4, 1910. Serial No. 565,058.

To all whom it may concern:

Be it known that I, RICHARD J. SCHWEITZER, a citizen of the United States, residing at Chicago, in the county of Cook and State 5 of Illinois, have invented certain new and useful Improvements in Sealed Joints, of which the following is a specification.

The present invention relates to means for producing a joint between an elbow pipe extending between the soil-stack and the bowl 10 of a lavatory fixture.

One of the objects of the present invention is to form a connection between the fixture and elbow pipe, which will embody a 15 seal to prevent the escapement of gas between the fixture and pipe, said seal being formed by pouring sealing substance into a well or trap formed at the upper end of the pipe, the well or trap being so located that 20 water flowing from the bowl will enter thereinto to a greater or less degree and cooperate with the sealing substance to form a continuous unbroken seal within the trap, which will effectively prevent the escapement of 25 gas from the elbow to the interior of the room, the water serving to fill any air-holes or other imperfections which may be formed in the sealing substance; and a further object is to so construct the trap that the water 30 will not reach the upper edge thereof and overflow to the outside of the joint.

A further object of the invention is to so form the walls of the thimble and trap that a wedging action will result when either one 35 of them is placed under a strain tending to move it vertically out of normal position.

Another object is to provide means for securing a sealing substance between the floor of the bowl and the top of the thimble; and 40 a further object is to so position the parts as to enable a sealing substance to be poured into the trap from either the outside or inside of the fixture.

The invention further consists in the features of construction and combination of 45 parts hereinafter described and claimed.

In the drawings, Figure 1 is an elevation partly in section, showing the elbow attached to the fixture and to the soil-stack; and Fig. 50 2, an enlarged sectional detail taken on line 2-2 of Fig. 1.

The device as shown is employed with a 55 lavatory fixture 3 positioned upon a floor 4; and the fixture comprises a bowl 5 terminating in a flange 6 resting upon the floor. The bowl is provided with a fluid passage-

way 7, as is usual and well known in devices of this nature. The fixture is recessed on its bottom to provide a circumferential chamber 7^a, into which is entered the horizontal flange 8 of a thimble 9, the vertical portion 10 of which extends downwardly and lies within a trap or well 11.

The upper surface of the horizontal portion 8 is formed with a circumferential groove 12^a, into which is inserted a ring of suitable packing material 13^a, which forms a seal between the thimble and fixture to prevent the leakage of gas there between; and the horizontal portion extends inwardly beyond the vertical portion and encircles and rests against a downwardly depending sleeve 14 formed with the body of the bowl 5 and extending from the fluid passageway 7 therein.

A trap or well 11 is formed adjacent to the upper end of an elbow pipe 12, which pipe, as shown in Fig. 1, enters into a soil-stack 13 of any usual and well known construction. The trap or well is formed between the walls of the upper end 15 of the pipe 12 and the walls of a circumferential, upwardly extending collar 16, which is formed integral with the pipe 12.

It will be noted that the upper edge of 85 the collar 16 lies above the upper edge of the pipe 12. This forms a shield which prevents the flowing of water over the upper edge of the collar to the outside of the pipe and into the room, which, of course, 90 would be objectionable. It will be seen by a study of the drawings that the water under ordinary conditions will never rise above the top of the pipe 12, and this point will determine the height to which water 95 can rise within the thimble 9. And since the collar 16 extends a substantial distance above the upper edge of the pipe 12, obviously even though the water be forced by some unusual condition above the edge 100 of the pipe, it cannot be raised sufficiently above its own level, which is the top of the pipe 12 to overflow.

In pouring the sealing substance into the well or trap 11, it sometimes happens that 105 through certain chemical actions bubbles and air-holes are formed therein. If sufficient of these are present, it might cause an outlet of gas, so that it would escape around the juncture of the pipe and thimble. But 110 in the present construction this would be prevented by the water which would collect in

the trap, as this water would flow down and fill up any crevices or holes of the above described nature and form a continuous seal which would effectively prevent the escape-
5 ment of gas at the juncture of the thimble and pipe. The water will be readily gathered in the trap by reason of its striking against the top of the pipe in passing from the fixture into the pipe and splash-
10 ing into the trap.

While in the drawings the sealing substance is shown as practically filling the entire trap, it is not necessary with the present construction to have this amount of
15 sealing substance, as enough only need be inserted in the trap to surround the bottom of the thimble 9 and prevent movement of the thimble with respect to the fixture. This is possible because of the water which
20 will flow into the trap and form a seal irrespective of the sealing substance. And, although the thimble is secured to the fixture by means of bolts 17, it is deemed
25 more practicable in actual operation to provide some fastening means for the ends of the thimble; hence, a quantity of sealing substance may be placed in the well which would be sufficient to surround the lower end of the thimble and thus anchor it in
30 position. The sealing substance employed could, of course, be of any usual and well known composition, such, for instance, as lead—which would be poured therein in a molten condition,—or, cement, or various
35 other compositions which harden and produce a solidified mass.

In positioning the sealing substance, it can be done by various methods: The thimble and fixture can first be assembled;
40 then the sealing substance can be poured into the trap or well and the thimble then inserted in place within the well. Or the thimble can first be inserted and the sealing substance poured into the well; and then
45 the fixture positioned upon the thimble. Or the thimble and fixture can first be assembled in operative positions with respect to the pipe and the sealing substance poured through the opening 18 at the upper end of
50 the collar 16.

Leaking of gas between the fixture and the thimble is prevented by means of the packing ring 13^a, and this, together with the seal effected within the trap 11, forms
55 a closure to prevent passage of gas in any direction save through the pipe 12, which conducts it into the soil-stack 13, as is desired in the operation of devices of this nature.

60 By utilizing a thimble setting into a trap as a means for effecting a connection between the pipe and fixture, any inequalities of the floor which may be present are compensated for by reason of the possible degree
65 of adjustment of the thimble within the

trap. Hence, no matter whether the floor be exactly on a true level or not, a tight connection can be made between the pipe and fixture, which will prevent the escape-
70 ment of any gas therebetween.

As shown in the drawings, the lower end of the thimble 9 is formed with a sloping surface 19 on the interior thereof, and this coöperates with a sloping surface 20 formed on the outer wall of the end 15 of the pipe 75 12, to prevent vertical movement of either the pipe or thimble out of normal position, as upon such movement the sloping faces 19 and 20 will be drawn closer to one another, thus wedging the sealing substance inter- 80 posed therebetween, which wedging will tend to check the movement of the sections, and obviously, the greater the strain and the greater the movement between the sections, the tighter will the sealing substance be 85 wedged and the greater the resistance offered thereby to the movement of the thimble or pipe.

By interposing the thimble into the well or trap in the manner shown in the drawings, gas, in order to escape by the thimble, will have to pass beneath the lower edge thereof; and since the lower edge is lying close to the bottom of the trap, it follows that the gas will have to force its way down- 95 ward and then upward through the entire mass of sealing substance lying within the trap.

I claim:

1. In a sealed joint, the combination with 100 a lavatory fixture of a thimble secured with respect to the fixture and extending downwardly and surrounding the fluid passage in the fixture, a pipe located in alinement with the thimble and the fluid passage in 105 the fixture, and provided at its upper end with a trap adapted to receive the lower end of the thimble, the lower end of the fluid passage being spaced away from the upper edge of the trap, whereby a portion of the fluid passing out of the fixture enters 110 the trap and assists in the sealing operation, said trap forming a chamber for the reception of sealing substance, whereby a seal is provided between the thimble and the pipe, 115 preventing leakage of gas therebetween, substantially as described.

2. In a sealed joint, the combination with 120 a lavatory fixture of a thimble secured with respect to the fixture and extending downwardly and surrounding the fluid passage in the fixture, a pipe located in alinement with the thimble and the fluid passage in the fixture, and provided at its upper end with a trap adapted to receive the lower end of the thimble, the lower end of the fluid passage being spaced away from the upper edge of the trap, whereby a portion of the fluid passing out of the fixture enters the 125 trap and assists in the sealing operation, said 130

trap forming a chamber for the reception of sealing substance, whereby a seal is provided between the thimble and the pipe, preventing leakage of gas therebetween, and 5 an inwardly extending flange on the thimble, engaging the fixture and serving to maintain the thimble in fixed relation to the pipe and fixture, substantially as described.

3. In a sealed joint, the combination with 10 a lavatory fixture of a thimble secured with respect to the fixture and extending downwardly and surrounding the fluid passage in the fixture, a pipe located in alinement with the thimble and the fluid passage in 15 the fixture, and provided at its upper end with a trap adapted to receive the lower end of the thimble, the lower end of the fluid passage being spaced away from the upper

edge of the trap, whereby a portion of the fluid passing out of the fixture enters the 20 trap and assists in the sealing operation, said trap forming a chamber for the reception of sealing substance, whereby a seal is provided between the thimble and the pipe, preventing leakage of gas therebetween, and 25 an inwardly extending flange on the thimble, engaging the fixture and serving to maintain the thimble in fixed relation to the pipe and the fixture, and a circumferential groove in the upper face of the flange, 30 adapted to receive and retain a ring of sealing substance, substantially as described.
